UNITED STATES PATENT OFFICE

MEYNARDIE NELSON, OF LITTLETON, NORTH CAROLINA; SUE J. NELSON ADMINISTRATRIX OF SAID MEYNARDIE NELSON, DECEASED

VERTICAL PAPER CUTTER

Application filed September 25, 1924. Serial No. 739,785.

This invention relates to vertical paper-cutters such as are adapted to be used for carrying rolls of wrapping paper and cutting the desired lengths of paper from the roll. My present improvements have particular relation to that type of paper cutters which embody a stationary base upon which is mounted a revolving base adapted to sustain and carry the roll of paper, a vertical standard or upright extending from said stationary base and having at its top a socketed end in alignment with the axis of the revolving base, the revolving base having an axial stud or projection for entering the bottom of the bore-block of the roll of paper, a retaining pin slidably mounted in the top socket of the standard and adapted to enter the top end of the bore-block of the roll of paper, lateral arms carried by and extending from the standard and spring-controlled by action of coiled springs carried by the standard, and a cutting blade carried at the outer end of said arms and adapted to bear against the side of the roll of paper, this general type of vertical paper-cutter being indicated in my previous Patent No. 1,116,834, of November 10, 1914, as well as other of my previous patents related to paper cutters of this general type.

The object of my present improvements is to provide a vertical paper-cutter of the type indicated, which will possess advantages in point of special features of construction, convenience, adaptability, effectiveness, durability, and general efficiency.

In the drawings—

Figure 1 is a perspective view of the improved paper cutter embodying my present improvements.

Fig. 2 is a vertical sectional view, on an enlarged scale, of the base portion of the device, intersecting the stationary base construction and the revolving base.

Fig. 3 is a detail vertical section on the line 3—3, Fig. 2.

Fig. 4 is a plan view of the under side of the base portion.

Fig. 5 is a detail perspective view illustrating the spring-control of the lower blade-carrying arm.

Fig. 6 is a vertical sectional view, on an en-

larged scale, of the top portion of the device, intersecting the retaining-pin member and its twine-holding means.

Fig. 7 is a detail cross-section on the line 7—7, Fig. 6.

Fig. 8 is a detail cross-section on the line 8—8, Fig. 6.

Fig. 9 is a detail cross-section on the line 9—9, Fig. 6.

Corresponding parts in all the figures are denoted by the same reference characters.

Referring to the drawings, 14 designates the horizontal stationary base portion which carries the revolving base, 15, above its top surface, and from which extends, at a point beyond the periphery of said revolving base, the vertical standard or upright, 16, in a position parallel to the side wall of the roll of paper, said standard having its top end turned at an angle to its stem and provided with a vertical-socket piece, 17, in alignment with the axis of the revolving base. 18—18 designate the blade-carrying arms, which have a turnable mounting upon the stem of the standard and project laterally therefrom and are controlled in the pressure action of the cutting blade upon the roll of paper by the spring means, as at 19, carried by the standard and engaging said arms, the cutting blade, 20, being carried at the ends of said arms 18 in alignment with the side of the roll of paper which is sustained and carried by the revolving base. 21 designates the retaining pin, which is slidably mounted in the socket-piece 17 and enters the top of the bore-block of the roll of paper. The roll of paper is indicated at 22 and its bore-block at 23.

The socket-piece 17 has a vertical tubular body, 24, and is preferably constituted by a stamped metal sheet bent at its central portion to form said tubular body which constitutes the socket for receiving the retaining pin 21, and having the lateral wings of said plate, as at 25—25, segmentally turned to conjointly form a tubular extension which receives the terminal end of the top of the standard 16 and is suitably secured thereto, as by a cross rivet, 26, the standard being 100

turned at its top, as at 27, at right angles to its stem, which turned top portion projects over the roll of paper.

My present improvements comprise means for controlling the bore-block of the roll of paper and regulating the bore diameter with relation to the diameter of the retaining pin 21. The preferred construction for this purpose embodies a ferrule, 28, constituting a tubular collar which is slidably mounted upon the retaining pin, beneath the socket member 17, and has its circumferential surface tapered downwardly, as at 29, which ferrule or collar enters the top of the bore-block and serves to reduce the bore thereof in relation to the retaining pin and thus adapt the varying diameter or sizes of the bore in different rolls of paper to the uniform diameter or size of the retaining pin 21. Supplementary to said bore-regulating means, a coiled spring, 30, is mounted upon the retaining pin and tensionally acts between the bottom of the tubular body 24 of the socket-piece 17 and the top of the ferrule or collar 28, said spring thus serving not only to retain the bore-regulating ferrule within the bore-block of the roll of paper but also to hold the bore-block downwardly in normal position within the paper roll and preclude any tendency of said block to ride upwardly on the retaining pin 21, which tendency is due to friction when the roll of paper is turning under conditions of use. The coiled spring 30 is preferably carried by the regulating ferrule and for this purpose the top end of the latter, above its taper surface, is preferably provided with a circumferential shoulder, 31, above which is formed a circumferential groove or recess, 32, receiving the end of the spring, 30, whereby the spring embraces said groove and is thus connected to the ferrule.

The retaining pin 21, in my present improvements, is provided at its top, above the socket-piece 17, with a revolving base or plate, 33, which preferably has a ball bearing. In the preferred construction, said ball bearing is constituted by an annular cup, 34, which may be stamped from sheet metal, mounted at the top end of the retaining pin 21, and having a downwardly-extending body flange, 35, entering and secured within the top end of the retaining pin, the latter being in this preferred construction preferably tubular. Said ball-cup carries a set of balls, 36, upon which the revolving base or plate 33 rests and bears, and said revolving base carries an axial pin, 37, extending downwardly from its under side and within the ball-cup member. Said axial pin is also projective above the revolving base 33, as at 38, and turns therewith and is tubular. To retain the revolving base-plate upon its ball bearing and to prevent upward movement of said base, a lock-pin, 37, is inserted longitudinally through

the tubular axial pin 37, and is headed at its top, as at 40, above the top extension 38 of the pin 37, and also headed or shouldered at its bottom, as at 41, in connection with the ball-cup member, said stationary lock-pin 39 thus constituting a vertical spindle upon which the axial pin 37 of the revolving base 33 turns.

The top revolving base 33 serves as a twine holder and is adapted to support and carry cones or spools of twine, as indicated at 42, of varying sizes. To enable the detachable mounting of such twine-spoils upon said carrying base, the top projecting extension 38 of the axial pin 37 is threaded, and upon said threaded extension is mounted a detachable tubular retaining pin, 43, having a threaded bore, which pin is received by the bore of the cone or spool of twine and is thus operative to retain the latter in position upon the sustaining revolving base 33.

In conjunction with the twine-holding means, which constitutes the top portion of the main retaining pin 21, as just described, a guide bracket is provided for the free end of the twine, to guide the same to convenient and suitable position at the rear of the cutter device and away from the general operative and paper-cutting mechanism. In the preferred construction, said guide bracket, 44, is carried by the horizontal top portion or arm 27 of the main standard or upright 16, and consists of a right angular strip or plate forming a vertical arm, 46, in parallel relationship to the spool of twine, and a horizontal arm, 47, projecting rearwardly therefrom, the terminal ends of each of said arms having a tubular eye-piece, 48, the bores of which are in a plane diagonal to the vertical plane of the revolving ball of twine, whereby the free end of the twine feeds through said eye-pieces downwardly and rearwardly and is guided away from the general operative mechanism of the device. The twine guide-bracket is secured in position preferably by means of a U-plate, 49, carried by its horizontal arm 47 and downwardly embracing the top arm 27 of the standard 16 and clamped thereon by a cross-pin or screw, 50, passing through the ends of the U-plate beneath said standard-arm 27.

The improved twine-holding means, as comprised in my present improved construction of paper cutter, is a part of the main insertible and detachable retaining pin 21 by which the roll of paper is mounted in its operative position upon the main revolving base 15, but under some circumstances of use the twine-holding main retaining pin 21 may not be employed, and in these conditions of use a substitute main retaining pin merely having a head at its top end, above the socket-piece 17, may be employed, as in my previous patents heretofore mentioned.

It will be noted that such a head or operative finger-piece, as at 51, is provided at the top of the supplementary retaining pin 43 which maintains the cone or spool of twine, said head being, in the present construction of twine-holding retaining pin, the main head or finger-piece by which the retaining pin 21 is operated in its slidable movement in the socket-piece 17 for insertion in or withdrawal from the bore-block of the roll of paper.

In my present improvements, the base portion of the device, which constitutes the stationary base, comprises a heavy metallic annular ring-plate or frame, 52, having a lateral extension, as at 53, forming the part at which the main standard or upright 16 is mounted, said extension being provided with a cylindrical opening, 54, and being preferably concaved at its under face circumferentially of said opening, as at 55. Said ring-plate constitutes the main body or frame of the stationary base portion, and serves also to counterbalance the complete cutter device in its vertical position without requiring the attachment of the device to a counter or other support. The top of said base portion is constituted by a plate, 56, preferably stamped from sheet metal and conforming to the circumferential contour of the ring-plate 52, the body portion of said top plate being preferably concaved at its under side, as at 57, to form a raised top surface beneath the revolving base 15 and within the area of the internal annulus of the ring-plate 52, a corresponding concaved and raised portion being also preferably provided, as at 58, above the extension portion 53 of the ring-plate 52. The top plate 56 has a circumferential flange, 59, extending downwardly at the sides of the ring-plate 52 which forms the counterbalance weight and frame of the base portion, and in the preferred stamped construction of the top plate 56 this edge flange is crimped to said ring plate in effective and secure attachment between said parts, as indicated at 45, and an elastic support or rest, as at 60, of rubber or other suitable material, is preferably secured to the weight-frame or ring-plate 52, to provide the contacting support by which the cutter device is mounted upon a counter or in any other suitable operative position.

In the central raised portion of the top plate 56 is provided an annular ball-cup, preferably by stamping a concave in the top of the plate, as at 61, carrying a set of balls, 62, upon which the revolving base 15 rests and is supported in a ball bearing. Said main revolving base 15 has an axial upwardly-projecting tubular stud, 63, which enters the bottom of the bore-block of the roll of paper, and through this stud extends a retaining pin, 64, headed above the stud, and

having its lower end passing through the top plate 56 axially of the ball bearing and riveted, as at 65, at the under side of said plate. The riveted pin 64 is provided with a shoulder, as at 66, which operates to prevent wear of the revolving base-plate 15 or "crowding" of the balls and to thus ensure the maintenance of the desired uniform space or distance between the revolving base 15 and the top plate 56 of the stationary base portion, which space is usually very minute to permit just the required play of the balls, for instance, 5/1000ths of an inch.

In my present improvements, the main standard or upright 16 is not only detachably connected with the main base portion 14 of the device in its mounting thereon, but is also adjustably mounted for variation vertically. In the improved construction, a socket-piece, 67, receives the lower end of the standard 16, said socket being preferably stamped in its contour and construction from sheet metal (as, for instance, aluminum) and comprising a tubular body, 68, forming a vertical socket opening in which the lower end of the standard snugly fits. This socket-piece 67, is secured in connection with the top plate 56 of the stationary base portion, and has its tubular body passing through a corresponding opening, 69, in the concaved and raised portion 58 of said top plate above the cylindrical opening 54 of the weight-ring or frame 52, said tubular body of the socket-piece having a lateral circumferential flange, as at 70, seated upon the top portion 58 of the top plate 56, and a lateral circumferential bottom flange, as at 71, crimped and thus riveted against the underside of said top plate. The tubular body 68 is externally threaded, as at 72, above the securing flange 70, and carries an adjustment nut, 73, and its wall at the top portion is recessed or notched at diametrically-opposite sides, as at 74—74, said recesses extending downwardly from the top edge a suitable distance in the externally-threaded portion of the body.

The standard 16 is threaded at its lower end, as at 75, and is provided at a suitable distance above said thread with diametrically-opposite laterally-projecting studs, 76—76, adapted to seat in the recesses or notches of the tubular body 68 of the socket-piece 67, and the threaded end of the standard carries a nut, 77, adapted to be set against the concaved under side 55 of the extension 53 of the weight-ring or frame 52, the lower end of the standard projecting through the opening 54 therein. Thus, when the standard is attachably mounted in connection with the stationary base portion, it is retained against vertical movement by the nut 77, and against lateral movement by its studs 76 in engagement with the recesses 74, and normally said studs are seated at the base of said recesses to lock the position of the standard in con-

nection with the securing nut 77. The improved construction, however, permits vertical adjustment of the standard in secured position, for the purpose of adjusting the relation of the cutting blade 20 to the main revolving base 15 in a vertical plane, this adjustment being desirable with relation to sizes or conditions in the roll of paper 22. In this connection it will be understood that by loosening the bottom nut 77, and moving the adjustment nut 73 upwardly, the standard will be lifted to the desired degree and correspondingly lift the cutting blade which it carries, when the studs 76 in the recesses 74 will then rest upon the adjustment nut 73, and the bottom nut 77 can be again tightened up to secure the standard in such adjusted position. A corresponding reverse movement and manipulation of the parts will of course effect an adjustment and securing of the standard in a relatively lowered position.

The springs, 19, which are carried by the standard and engage the arms 18 to control the action of the cutting blade, are preferably provided with a terminal bottom eye, 78, receiving a headed cross-pin, 79, passing through the standard 16 and riveted in position and projecting at opposite sides thereof, as at 80, the coil of the spring which surrounds the standard being thus supported upon the projecting ends of the cross-pin 79, and retained in normal tension between said ends and the blade-carrying arm 18, which thus retains the spring at constant uniform tension. The free end of the springs, thus securely mounted in a reverse coil, is projected forwardly beneath the blade-carrying arm 18, as at 81, and extends upwardly at the side thereof, as at 82, and over the top edge of the arm, as at 83, so that the position of the arm revolvably upon the standard is retained beneath the top end 83 of the spring and the bottom eye 78 thereof in connection with the cross-pin 79.

The operation of the device, and the advantages attained by my present improvements as herein described, will be readily understood from the foregoing description.

The improved features of construction provide not only enhanced and essential conditions of strength and accurate and effective operation and counter-balance, but produce an improved vertical paper-cutter affording special advantages in point of convenience and adjustability in service and use, and economy in the conditions of manufacture and general features of construction.

I do not desire to be understood as limiting myself to the detail features of construction as herein shown and described, as it is manifest that variations and modifications therein may be resorted to, in the adaptation of my invention to varying conditions of use, without departing from the spirit and scope of

the invention and improvements. I therefore reserve the right to all such variations and modifications as properly fall within the scope of my invention and the terms of the following claims.

Having thus described my invention, I claim and desire to secure by Letters Patent:

1. In a vertical paper cutter of the class described, comprising means for revolvably carrying and supporting in vertical position a roll of paper wound upon a bore-block and a frame having a tubular socket mounted to be in vertical alignment with the axis of the bore-block when the paper roll is in position and to afford a free space above the upper end of the block, a retaining pin mounted in said tubular socket and adapted to enter the bore-block, a collar or ferrule having a bore receiving said retaining pin and slidably mounted thereon and provided with an external surface of varying diameter for entering the bore-block, whereby the varying diameter or sizes of the bore blocks of different rolls of various sizes of paper will be adapted to the uniform diameter or size of the retaining pin, and tensional means positioned upon said retaining pin below said socket member and mounted to exert its pressure downwardly against the collar or ferrule to resist an upward slidable movement thereof and thus tensionally maintain the adjustment of said collar with relation to the bore-block and tensionally control the tendency of the block to ride upwardly in the bore of the roll of paper under the lateral pull thereon when the latter is turning.

2. In a vertical paper-cutter of the class described a stationary base, a revolving base carried by said stationary base for sustaining a roll of paper, an upright or standard carried by said stationary base, a cutting blade carried by said standard and mounted for operative relation to the paper roll, a tubular socket carried by the stationary base and having notches or recesses extending downwardly in its wall from the top edge, the lower end of the said standard being received by said socket and being detachably secured at the under side of the stationary base and said standard being provided with lateral studs or pins received by said recesses or notches, and means vertically operative upon said socket with relation to said studs and recesses to adjustably vary the operative position of the standard.

3. In a vertical paper-cutter of the class described, a stationary base, a revolving base carried by said stationary base for sustaining a roll of paper, an upright or standard carried by said stationary base, a cutting blade carried by said standard and mounted for operative relation to the paper roll, an externally-threaded tubular socket carried by the stationary base and having notches or recesses extending downwardly in its wall

from the top edge, the lower end of said standard being threaded and received by said socket and having lateral studs or pins received by said recesses or notches, a set nut securing the standard at the under side of the stationary base, and an adjustment nut operative upon the threaded socket with relation to said studs or pins and said notches and recesses.

4. In a paper cutter of the class described, a standard, a cutting blade carried by said standard and mounted for operative relation to a roll of paper, a mounting socket receiving the end of said standard, means for positionally securing the standard in said socket, means for adjustably varying the operative secured position of said standard in its connection with the mounting socket for altering the position of the cutting blade with relation to the paper roll, and supplementary means for locking the connection of the standard with said socket at any of its variable steps of adjustment.

5. In a paper cutter of the class described a standard, a cutting blade carried by said standard and mounted for operative relation to a roll of paper, a mounting socket receiving the end of said standard and provided with seating means engaged by the standard against lateral movement thereof, adjustable means for positionally securing the standard in its seated connection with said socket, and supplementary adjustment means carried by the socket for varying the seated connection of the standard therewith, whereby the operative secured position of the standard may be varied for altering the position of the cutting blade with relation to the paper roll.

6. In a paper cutter of the kind described for revolvably mounting in vertical position, a roll of paper having a bore-block, the combination of a stationary base, a revolving base mounted thereon to support the roll of paper and the bore-block, a standard attached to the stationary base and having one end extending over the roll of paper, a retaining pin carried by the standard to project into the bore-block, a tapered ferrule on said pin to enter the bore-block, and a spring for forcing the ferrule into the bore-block, whereby paper rolls having bore-blocks of varying inside diameters can be disposed in said paper cutter.

7. In a paper cutter of the kind described, the combination of a stationary base, a revolving base carried by the stationary base for supporting a roll of paper thereon, a standard attached to the stationary base, a cutting blade carried by the standard to engage the outside of the roll, means for adjusting the standard with respect to the base, one end of said standard extending over the roll of paper, and means comprising a spring 85 pressed tapered member on said end of the

standard extending into the bore-block of the roll of paper.

8. In a paper cutter of the class described, comprising means for revolvably carrying a roll of paper wound upon a bore block, a frame, a tubular socket in said frame and in alignment with the axis of the bore block when the paper roll is in position and to afford a free space on one end of the block, a retaining pin movably mounted in said tubular socket and adapted to enter the bore block, a tapered ferrule freely mounted on said retaining pin between the socket, and the bore block and a tensile device mounted between said socket and said ferrule and mounted to force said ferrule against one end of the bore block when the paper roll is in position and resiliently oppose the tendency of the block to move in the bore of the roll of paper under the lateral pull thereon when the latter is turning.

In testimony whereof I have signed the foregoing specifications.

MEYNARDIE NELSON.
